CLAIM

The ornamental design for a greenhouse lamp, as shown and described.

DESCRIPTION

FIG. 1 is a perspective view of a first embodiment of a greenhouse lamp showing our new design;

FIG. 2 is a perspective view thereof;

FIG. 3 is a front elevational view thereof;

FIG. 4 is a left side elevational view thereof; The right side view is a mirror image of the left side view.

FIG. 5 is a rear elevational view thereof;

FIG. 6 is a top plan view thereof;

FIG. 7 is a bottom plan view thereof;

FIG. 8 is a perspective view of a second embodiment of a greenhouse lamp showing our new design;

FIG. 9 is a perspective view thereof;

FIG. 10 is a front elevational view thereof;

FIG. 11 is a left side elevational view thereof; The right side view is a mirror image of the left side view.

FIG. 12 is a rear elevational view thereof;

FIG. 13 is a top plan view thereof; and,

FIG. 14 is a bottom plan view thereof.

The broken lines immediately adjacent the shaded areas represent the bounds of the claimed design while all other broken lines depict portions of the greenhouse lamp that form no part of the claimed design.
